UNITED STATES PATENT OFFICE.

BUTLER F. GREER, OF SAN FRANCISCO, CALIFORNIA.

SAVINGS BANK.

Application filed April 6, 1927. Serial No. 181,348.

This invention relates to improvements in savings banks and more particularly to small savings receptacles, of the type where-in the savings are placed at intervals and 5 periodically conveyed to the savings bank or institution in which the savings or contents of the receptacle are deposited at interest. Such receptacles for savings are usually kept about homes or business offices 10 and are apt to excite the cupidity of dishonest persons. It has been the practice to disguise such receptacles in some manner to afford a measure of protection against pilfering. In this connection I cite my Patent 15 No. 1,460,716, issued on the third day of July, 1923, entitled Book form savings banks, in which the money receptacle is disguised in the form of a book.

In the present instance the receptacle is 20 disguised as a picture frame, having combined therewith elements disguising its nature and contributing to the safety of the contents and its commercial desirability, by 25 its improved appearance, which is one of the objects of this invention. Another object is to provide a pedestal base adapted to hold the bank in an upright position, yet which may be easily and unobtrusively dispensed with when the receptacle is being 30 carried to the bank. Other objects and advantages will appear as this description progresses.

In this specification and the annexed drawings the invention is illustrated in the 35 form considered to be the best, but I do not wish to be understood as confining it to this form, because it may be embodied in other forms, and it is also to be understood that in and by the claims following the description 40 it is desired to cover the invention in whatsoever form it may be embodied.

In the accompanying one sheet of drawings, Fig. 1 is a front elevation of a coin receptacle with a pedestal base constructed in 45 accordance with this invention. Fig. 2 is a perspective view of the same from the side and rear, showing the locked door partially open to disclose the interior construction. Fig. 3 is a side elevation of the same 50 partially broken away in section to disclose the construction and combination of the removable pedestal base.

In detail the construction illustrated in the drawings comprises a rectangular money receptacle having the closed back 1, the sides 2 and 3 and the ends 4 and 5. The swinging

cover 6 is hinged at 7 to the edge of the side 2 and is provided with the notched detents 8—8, forming part of the plate 9 that is spot welded or otherwise secured to the cover 6, whereby the cover may be locked by suitable wards, not shown, controlled by a key introduced into the keyhole 10, in the conventional manner. When the cover 6 is unlocked it is thrown to the open position 65 shown in Figure 2 by the tension of the leaf spring 11 riveted to the side 2 and bearing under the cover 6. The top end 5 is provided with the coin slot 12 protected by a non-return mechanism such as 13, adapted 70 to prevent coin from being shaken out of the receptacle through the slot 12, after once having been introduced. The construction of this receptacle is described more in detail in the patent issued to me, above cited. 75 Such a receptacle is adapted to protect its contents against access by unauthorized persons.

As a further protection, the receptacle is 80 provided with an enclosing frame encircling the sides 2 and 3 and the upper end 5, but of slightly greater depth so that it projects to the rear, flush with the outer plane of the door 6 and slightly beyond the back plate 1, where it is flanged inward at 15, 16 and 17. 85 These flanges are spaced away from the back 1 a sufficient distance to allow for the insertion of a picture 18 therebetween, which may be protected by a sheet of glass 18', also inserted between the flanges and the 90 back 1.

The ends of the frame 14 are cut away at 95 19 and the extensions thereof bent under the end 4 as at 20. These ends 20 form guides to receive the plate 21 which completes the frame 14 beneath the end 4. This base plate 21 is provided with the flange 22, which completes the flanges 15, 16 and 17 to form the bezel of the picture frame. The plate 21 is held in position by frictional engagement 100 with the guides 20. These guides are cut away at 19 so as not to show the bent under portion 20 when viewed from the front, as in Fig. 1.

To cause the combined money receptacle and picture frame to assume the characteristics of a picture frame it is caused to stand upright in an easel-like position as in Fig. 3, by the pedestal feet 23—23. These feet are formed of short lengths of sheet metal 105 strips having the scrolls 24 bent in one of the ends thereof and the opposite ends bent at a 110

slight angle as at 25. These feet are riveted as at 26 in embossments in the plate 21 adjacent its opposite ends in such a manner that the feet may be rotated on these rivets 26 and turned under the plate 21 as shown in Figure 1, the bends 25 causing resilient tension of the ends 27 against the surface of the plate 21, whereby the feet are frictionally maintained in the inoperative position shown in Fig. 1, in addition to the friction caused by the rivets 26 between the feet and the plate 21. These feet are held in the operative position shown in Fig. 3 by this latter friction, the frame resting upon the scrolls 24 and the ends 27 to maintain the bank in the upright position. The frame 14 is ornamented in a suitable manner to give all of the characteristics of a picture frame, for the purpose of combining with the money receptacle the element of disguise 20 for the purpose of protecting its contents.

When it is desired to convey the money receptacle and its contents to the savings bank for deposit, the feet 23 are turned under into the position shown in Fig. 1 making the receptacle more comfortably carried or conveniently enclosed with a shopping bag or purse. Such banks are handled in the majority of cases, by women and children who may become easy victims to purse snatchers while carrying a money receptacle that obviously discloses its function, if not disguised in accordance with this invention.

Having thus described this invention what I claim and desire to secure by Letters Patent is:

1. A savings bank having a locked opening; a frame attached to said receptacle and having a flange overhanging a portion of one side thereof; and a pedestal base slidably engaging said frame and having a flange completing the flange on said frame.

2. A savings bank comprising a money receptacle having a locked opening; a frame attached to said receptacle and having a

flange overhanging and spaced from a portion of one side thereof; guides on said frame; a pedestal base engaging said guides and having a flange completing the flange on said frame.

50

3. A savings bank comprising a money receptacle having a closed front and a locked back; a frame enclosing the sides of said receptacle and having a flange overhanging and spaced from said closed front; a flanged pedestal base engaging said frame and enclosing the fourth side of said case.

55

4. A savings bank comprising a money receptacle having a closed front and a locked back; a frame enclosing three sides of said receptacle and having a flange overhanging and spaced from said closed front, the ends of said frame being bent under the fourth side of said receptacle to form guides; a pedestal base slidably engaging said guides 65 and having a flange completing the flange on said frame.

60

5. A savings bank having a locked opening; a frame attached to said receptacle and having a flange overhanging a portion of one side thereof; and a pedestal base slidably engaging said frame and having a flange completing the flange on said frame; and feet attached to said base.

70

6. A savings bank having a locked opening; a frame attached to said receptacle and having a flange overhanging a portion of one side thereof; and a pedestal base slidably engaging said frame and having a flange completing the flange on said frame; so and resilient feet pivoted to said base.

75

7. A savings bank comprising a money receptacle having a locked opening; a frame attached to said receptacle and having a flange overhanging one side thereof; and pedestal feet pivoted to said frame.

80

In testimony whereof I have hereunto affixed my signature.

BUTLER F. GREER.
